UNITED STATES PATENT OFFICE.

JOSEPH R. DUMONT, OF KANSAS CITY, MISSOURI.

DIRECTORY-RACK.

1,209,819.

Specification of Letters Patent. Patented Dec. 26, 1916.

Application filed April 6, 1916. Serial No. 89,310.

To all whom it may concern:

Be it known that I, JOSEPH R. DUMONT, a citizen of the United States, residing at Kansas City, in the county of Jackson and 5 State of Missouri, have invented certain new and useful Improvements in Directory-Racks; and I do declare the following to be a full, clear, and exact description of the invention, such as will enable others 10 skilled in the art to which it appertains to make and use the same, reference being had to the accompanying drawings, and to the letters and figures of reference marked thereon, which form a part of this specification.

15 My invention relates to a directory rack, and more particularly to a device of that character for use in hotels or other places where the names of guests or other information must, for the sake of convenience, be arranged in alphabetical or other fixed order, and wherein the information contained in the rack is subject to change at frequent intervals.

20 The present invention is an improvement on the structure disclosed in my co-pending application, filed January 17, 1916, and serially numbered 72,440, and has for its principal object to provide an improved 25 rack, wherein information cards of substantial length may be carried without unduly extending the dimensions of the rack.

30 It is also an object of the present invention, to provide improvements in the construction of the rack frame.

35 In accomplishing these objects, I have provided improved details of structure, the preferred forms of which are illustrated in the accompanying drawings, wherein:—

40 Figure I is a perspective view of a rack, embodying the improvements noted. Fig. II is a transverse section on the line II-II (Fig. I). Fig. III is an enlarged vertical section of two of the individual traps in 45 their assembled relation. Fig. IV is an enlarged perspective view of two of the traps, particularly illustrating the mounting of 50 an information card in one of the traps, the trap being partly broken away for better illustration. Fig. V is a detail perspective view of the trap, containing a card 55 adapted for bearing information of a nature other than that indicated in Fig. IV.

Referring more in detail to the drawings:—The frame 1, as a whole, comprises

the side rails 2—3, which are spaced by the 60 end plates 4—5, and are preferably of angle construction, each of said rails having one member arranged at the outside of the frame to form a side wall and the other member 65 at the front of the frame to form a front wall, to provide an interior housing for the card traps and guides presently described. The end plates 4—5 are also preferably of angle construction, each having one section 70 extending over the top or bottom of the side rails, and its other section at the front thereof, the front sections being secured to the front wall sections of the side rails by bolts or screws 7 in order to permanently 75 and securely connect the side rails and hold the same in fixed spaced relation.

Lying along the back faces of the front 80 wall sections of the frame rails 2—3, and secured thereto by bolts or screws 8 are 85 guides 9, preferably comprising channel members, in order that one side of each channel may lie against the inner face of the adjacent side wall of the frame rail and the other member of the channel lie parallel with the side wall and serve as a guide 90 for the card traps presently described, and said channel members being inset from the inner edges of the front walls of the frame, in order to provide a guide space at the in- 95 side of said walls.

The frame just described is preferably composed entirely of metal in order to give it proper rigidity and permanency, and to provide smooth guide surfaces along which 90 the card traps may move.

The card traps used with the frame each 95 comprise a sheet of metal or other material that will give it permanency in form and shape, and which is bent upon itself to form the front and back portions 14—15, leaving an intervening space 16 within which the supporting head of an information card may seat.

Each trap is of slightly greater length 100 than the space between the facing edges of the front walls of the frame rails and of slightly less length than the distance between the facing members of the opposite guides 9, so that in order to position the 105 traps within the frame, they must be inclined as shown in dotted lines Fig. I, and when placed within the frame will assume position at right angles to the frame rails with the ends of the traps lying parallel 110.

with and closely adjacent the inner members of the guides (Fig. II).

In order to support the traps in the frame, I provide the front 14 of each trap with forwardly directed ears 18 that are adapted to rest on the upper edge of the bottom plate 5 of the frame, or on the upper edge of the back 15 of another trap, the said ears being preferably arranged at the outer ends of the front members 14, and provided with outwardly facing slots 19 for receiving the edges of the adjacent front walls of the frame rails, so that the traps may slide vertically along the frame and in guided relation thereto.

In order to better expose an information card that is carried in the trap pocket, I cut away the front 14 of the trap so that the card is exposed, and extend the back 15 above the ears 18, this extension of the back being arranged by forming the ears 18 on the upper ends of the arms 20 that are formed when the body of the front portion 14 is cut away to widen the exposure space 25 for the contained card. In the upper edge of the back portion 15 of each card trap is a cut out portion 15', forming a recess for the thumb of a person wishing to remove a card from the rack.

As it is desirable that the card traps seat as snugly as possible within the frame, to avoid lost motion and displacement of the traps, the ends of the traps should lie as closely as possible to the guides. In order 35 to secure this snug arrangement and still allow for tilting the traps in order that they may be located in the frame, I preferably cut away one of the upper corners of the back member 15, so that it slants relative to the 40 end line of the trap.

With this construction, when the trap is to be placed in or removed from the frame, it may be held at an angle, so that the inclined corner 21 lies flat against the inner 45 wall of the guide 8 while the trap is lowered to a position at right angles to the longitudinal line of the frame. After the trap has assumed its functional position the ends will lie parallel to the guides and hold the 50 trap snugly in position, until it is tipped by a person lifting on the ear 18 at the end opposite the inclined corner.

In my former application, I located the information cards wholly within the traps 55 and supported them in the bottoms of the pockets, so that all the information on the card was exposed above the cut out front portion of the traps.

For hotel and other uses, it is sometimes necessary to provide longer and wider cards that would necessitate deeper traps and limit the efficiency of the rack by limiting the number of traps which could be used therein. In order to obviate this disadvantage, I 60 provide for suspending the cards from the

traps, so that part of a card in one trap may lie back of a lower trap when the rack is idle, although the information contained on the lower portion of the card may be readily observable when the trap carrying a card 70 containing the information desired is lifted in the rack. In order to accomplish this result, I provide the bottom of each of the traps with a slot 23 and construct the cards 75 24 of a width that will enable the body portion thereof to project through the trap slot when it is inserted into the trap pocket from above, each card having a head 25 of greater width than its body portion, to provide the shoulders 26 that extend laterally beyond 80 the edges of the body of the card so that they may rest on the bottom portions of the trap at the ends of the slot 23. The heads 25 are of such depth that their top edges will be below the upper edges of the trap 85 when the cards are in place, and will be exposed to the same extent as the cards in my former application. The body portions of the cards are also exposed, but beneath the trap, so that information contained thereon 90 is obscured, except when the traps are lifted to expose the body portions.

Assuming that the parts are assembled and constructed as described and, for illustration, assuming that the rack is used for hotel purposes; when a guest arrives at the hotel, a clerk enters his name on the head of the information card, together with the number of the room to which he is assigned, and what other information of a general nature 95 may be desired.

The traps above the position that the card is to occupy are raised by lifting on the ear 18 opposite the incline 16' of the trap next above that position and the trap for bearing the new card is located in the rack as heretofore described. The card is then positioned in the rack by dropping the body 24 through the slot 23, so that the shoulders 26 will 105 hang on the bottom of the trap at the ends of the slot.

From time to time, while the guest is at the hotel, a bookkeeper, or a clerk, may make entries on the body of the card, removing the card from the slot for that purpose, and when the guest leaves, the trap may be taken 110 out of the rack and the card removed and transferred to a suitable file.

If the guest leaves a forwarding address, a card bearing the forwarding information 115 is substituted for the guest card, and the trap is either returned to the former rack, or placed in a rack especially assigned for forwarding cards.

While I have described a particular use of 120 the rack and particular types of cards, I do not wish to be understood as limiting the invention to such particular uses, or forms, but desire protection of a scope commensurate with the improvement.

Having thus described my invention, what I claim as new therein, and desire to secure by Letters-Patent, is:—

1. A rack trap comprising means for suspending a card and means for supporting the trap.
2. A rack trap comprising a back member, means at the front of said back for confining a card and means for suspending a card below the bottom of the trap.
3. A rack trap comprising spaced front and back portions, and a bottom having a longitudinally extending slot therein.
4. A rack trap comprising spaced front and back portions and a bottom having a longitudinal slot therein, the front of the trap being downcut from its upper edge, and having supporting ears at the ends of the side portions.
5. The combination with a suitable frame, of a trap comprising a pocket forming member, and a card having a head supported by the pocket forming member and a body extending below the trap.
6. A trap for card racks comprising a pocket forming member having a slotted bottom and a card comprising a body portion adapted for projection through the slot in said bottom and a head, having shoulders adapted for support on said bottom at the ends of the slot.
7. A rack trap comprising spaced front and back members, the back member having its edge at one of its upper corners inclined relative to the end of the trap.
8. A rack trap comprising spaced front and back members, the back member having a thumb recess in its upper edge.
9. In a rack, a frame comprising spaced side rails having front and side walls and upper and lower connecting plates, and guides fixed to the inner faces of said front walls; and a trap adapted for travel back of the front walls and between the guides, and having slotted ears in guided relation to the facing edges of said front walls.

In testimony whereof I affix my signature.

JOSEPH R. DUMONT.
